(57) **CLAIM**

The ornamental design for a flan cubby, as shown and described.

DESCRIPTION

FIG. 1 is a perspective view of the flan cubby container showing my new design, shown without the lid for completeness of illustration;

FIG. 2 is a top plan view thereof;

FIG. 3 is a cross-sectional view taken through line A-A of FIG. 2;

FIG. 4 is a perspective view of the tray thereof, shown separately for ease of illustration;

FIG. 5 is a top plan view of the tray thereof;

FIG. 6 is a top plan view of the ring thereof, shown separately for ease of illustration;

FIG. 7 is an enlarged cross-sectional view taken through line A-A of FIG. 6;

FIG. 8 is a top plan view of the lid thereof;

FIG. 9 is a top plan view of the tray and container thereof, shown in a locked position;

FIG. 10 is a top plan view of the tray resting inside of container thereof;

FIG. 11 is a perspective view of the tray inside of container thereof;

FIG. 12 is a perspective view of the ring thereof;

FIG. 13 is a perspective view of the flan cubby container and lid thereof;

FIG. 14 is an exploded view showing the tray attached to the container thereof; and,

FIG. 15 is a top environmental plan view of tray showing how flan is sliced into eight equal slices thereof.

The broken lines shown in the drawings are for illustrative purposes only and form no part of the claimed design.
